(57) **CLAIM**

The ornamental design for a lever portion of video camera, as shown and described.

DESCRIPTION

FIG. 1 is a top, front perspective view of a lever portion of a video camera showing my design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is a top, rear perspective view thereof, wherein the lever portion is in the upright position.

The broken line showing of a video camera is to illustrate environment only and forms no part of the claimed design.
